SLITTER AND REWINDER

Bryant W. Langston, Woodbury, N. J., and Karl Sieg, Philadelphia, Pa., assignors to Samuel M. Langston Co., a corporation of New Jersey

Application August 4, 1942, Serial No. 453,528

22 Claims. (Cl. 164—65)

The present invention relates to slitters and rewinders of the type in which paper from one roll or other source is slit longitudinally into sections, and the sections are rewound to form separate rolls.

A machine of this type usually comprises two opposed sets of rotary knives arranged in mating pairs with the knives of each pair spring-pressed together in overlapping relationship at the point where the slitting takes place. These two sets must be separated to facilitate threading of the uncut web therebetween and resetting of the knives for a new run. For that purpose, one set of knives is first moved axially or laterally out of spring-pressed engagement with the other set, and then edgewise away from the plane of the paper. This lateral preliminary movement is necessary to prevent the cutting edges of one set of the mating knives from destructively snapping across the edges of the other set during their relative edgewise movement.

One object of the present invention is to provide means whereby the manipulative operations necessary to prepare a slitter andrewinder for a new run are reduced to a minimum.

As a feature of the present invention, the machine is provided one side with hand-operated means for effecting the two movements of the movable knife set, and on the other side with automatic means for locking said knife set in operative position against movement away from the plane of the paper or for unlocking it, according to the actuation of said hand-operated means.

As a further feature, a single lever handle is provided for effecting both movements of the knife set and for effecting the locking and unlocking of the knife carrier at both sides of the machine.

Thus all of the parts carrying the movable knife set are simultaneously locked or unlocked at opposite sides of the machine and by the operation of a single operating member at one side only of the machine.

Various other objects, features and advantages of the invention will be apparent from the following particular description, and from an inspection of the accompanying drawings, in which

Fig. 1 is a fragmentary front elevation partly in section and somewhat diagrammatic of a slitter andrewinder embodying the present invention, and shown with the knives in operative cutting position;

Fig. 2 is a fragmentary end elevation partly in section, the full lines indicating the normal op-

erative position and the dot and dash lines the thread up position of certain parts of the machine;

Fig. 3 is a section taken on line 3—3 of Fig. 1, but on a larger scale;

Fig. 4 is a perspective showing certain parts in operating position;

Fig. 5 is a top plan view showing the means for locking the lever mechanism and for predetermined the sequence of manipulative operation of said lever mechanism; and

Fig. 6 is a section taken on line 6—6 of Fig. 1, but on a larger scale.

In the particular embodiment of the invention selected for illustration in the drawings, the slitter andrewinder comprises a pair of frames 10 and 11 serving as supports for certain operating elements of the machine, such as the idler roll 12, the two opposed sets of rotary slitting knives 13 and 14, and the two power driven winding drums 15 and 16. The paper A to be slit is delivered from a suitable source such as a mill roll (not shown), and passes over the idler roll 12 and between the two sets of knives 13 and 14 where it is longitudinally slit to form strips of the desired width and trimmed at the edges. The slit paper A then passes over a guide bar 17, over the winding drums 15 and 16 and around a rewinding shaft 18 to form a roll of rewound paper B. This roll of paper is supported on the winding drums 15 and 16, and is frictionally driven thereby about the rewinding shaft 18 as an axis. To accommodate for the progressive increase in the diameter of the paper roll B, the rewinding shaft 18 may be supported for vertical movement in a manner similar to that shown in the Sieg Patent 1,827,802, and may be of the collapsible and sectional type to permit longitudinal separation of the separate rolls of slit strips.

The rear slitting knives 13 are adjustably mounted on a driven shaft 22 journalled in the frames 10 and 11.

The front slitting knives 14 are adjustably mounted on a bar 23 supported in the frames 10 and 11, and are spring-pressed axially into overlapping frictional driving engagement with the power driven knives 13. This slitter support bar 23 is formed with a trapezoidal tenon 25 receiving a plurality of clamp brackets 26 in dovetail adjustable slide relationship therewith, so that the knives may be adjusted along the bar to the desired positions and spacing and corresponding to the positions and spacing of the rear knives. To each of said brackets 26 is secured one end

of a spring plate 27, the other end of which carries a bearing 29 for a corresponding knife 14.

In operative position each front knife 14 overlaps a corresponding rear knife and is spring-pressed through the action of its spring 27 into engagement with one face thereof, so that the front knives are frictionally driven by the rear knives during slitting action.

To move the knives 14 axially out of engagement with the knives 13, and then edgewise out of overlapping relationship therewith, away from the plane of the paper, the front slitter support bar 23 is slideable in the frames 10 and 11, and has one end 30 projecting outwardly beyond the outer face of the frame 10 (Figs. 1 and 2). A lever 35 has a split hub 31 splined to the projecting end 30 of the bar 23 to rotate with said bar. Means are provided for holding this lever 35 against movement away from the frame 10 during manipulation thereof. As shown, a bushing 32 (Figs. 1 and 6) fixed in said frame and serving as a slide bearing for the bar 23 has an end flange 33 extending in a corresponding recess of the lever hub 31.

The lever 35 has journalled therein a shifter shaft 36 (Figs. 1 and 2) formed at one end with an eccentric stud projection 37 which is journalled in a shoe 38 set in a transverse slot or recess 39 of the bar 23, and which causes axial shifting of said bar upon rotation of said shaft about its axis. This shifter shaft 36 is provided with a crank handle 41 at its upper end whereby the shaft can be rotated, the bar 23 shifted axially, and the knives 14 moved axially away from their corresponding mating knives 13.

To lock the shifter shaft 36 against rotation when in normal operative position of the slitting knives 14, the handle portion of the crank 41 carries a spring-pressed lock pin 42 to which is connected a knob 43 at one end. A lock bracket 44 secured to the frame 10 is formed with an aperture 45 to receive the lock pin 42 in normal locked position of the shifter shaft 36 shown in full lines in Fig. 2.

To predetermine the extent of rotation of the shifter shaft 36 in moving the knives 14 axially to the desired distance and to lock it in this position, the lever 35 is formed with an arm 47 (Figs. 1, 2 and 5) having an aperture 46 spaced about 180° from the aperture 45 in the bracket 44 and adapted to receive the locking pin 42. To receive this arm 47 as well as the upper end portion of the shifter shaft 36 when the latter and the lever 35 are in normal position, the top wall of the lock bracket 44 is formed with a slot 48 (Figs. 2 and 5) open at one end and the other end 50 serving as a stop for said lever.

In the operation of the lever mechanism described, when it is desired to move the front slitting knives 14 away from the knives 13 in preparation for the next run, the locking pin 42 is retracted from the aperture 45 in the lock bracket 44, and the crank 41 and shaft 36 rotated about 180° until the lock pin 42 is in registry with the socket in the lever extension 47. Thus the bar 23 will be shifted axially in its side frame bearings towards the left (Fig. 1) through the action of the eccentric stud 37, and the knives 14 will be moved axially away from their respective mating knives 13.

To move the knives 14 edgewise away from the plane of the paper and into thread up position, the lever 35 is swung angularly into the approximate position shown in dot and dash

5 tation of the bar 23 in the frames 10 and 11, so that the knives 14 are swung angularly edge-wise away from the knives 13, whereby sufficient space is afforded between the two sets of knives 13 and 14 to facilitate adjustments in the position of said knives, and to facilitate the threading up of the uncut paper in preparation for the next run.

10 To limit the extent of angular movement of the lever 35 into thread up position, the lever hub 31 is formed with a depending extension 52 (Figs. 1 and 2), and the frame 10 carries a stop pin 53 adapted to engage this extension 52 in limiting angular position of said lever.

15 A counterweight 54 normally tending to maintain the lever 35 in the full line normal position shown in Fig. 2 facilitates the return movement of the lever 35 into this position.

20 Predetermined sequence in the two movements of the slitting knives 14 is assured by means of the shape of a collar 56 (Figs. 2 and 5) secured to the portion of the shifter shaft 36 which passes through the bracket slot 48. The collar has a flat chordal surface 57 on one side. The inner end section 58 of the slot 48 is circular and dimensioned to snugly accommodate and permit rotation of the collar 56, while the slot leading to the circular end section is narrower than the diameter of the collar. One side 25 of the slot 48 is tangential to the circular end section 58, while the other side 60 of the stop is positioned for sliding engagement with the chordal surface 57 of the collar 56. Thus the inner end of this side 60 forms a stop for the collar 56 when the collar is in the rotative position shown in Figs. 2 and 5. The lever 35 cannot be angularly shifted through the slot 48 of the lock bracket 44 unless the collar 56 has its flat chordal surface 57 against the slot edge 60. This assures proper sequence in the two phases of 30 movement of the knives 14, and also acts in addition to the pin 42 and aperture 45 to lock the set of knives 13 against movement away from the plane of the paper.

35 The machine is also provided with a series of spreaders 65 (Figs. 1 and 4) serving to lead the cut portions of the web away from each other along the lines of severance and thereby create a slight gap between adjoining sections, so as to 40 make it easier to separate the several rewound rolls B. These spreaders 65 are mounted to move with the slitting knives 14 away from the paper web. For that purpose there is provided a spreader support bar 66 which is pinned or otherwise affixed at one end to the lever 35, and which 45 is slidably mounted at its other end to a lever arm 67 (Fig. 1) secured at one end to the slitter support bar 23 adjacent the inner face of the side frame 11. A spreader bar 68 (Figs. 1 and 4) 50 is secured to the support bar 66 in parallel relationship therewith by studs 70 or other suitable means, and carries the spreaders 65 along one edge thereof. For adjustably supporting these spreaders 65 in selective position along the 55 spreader bar 68, said bar is formed with a dovetail channel 72 to snugly receive the dovetail tenons of a plurality of clamps 73 (Fig. 4). These clamps 73 are secured to respective holders 74 by means of studs 75 to hold said clamps 60 73 in adjusted position on the spreader bar 68. Each holder 74 pivotally carries a corresponding spreader 65 in the form of a lever bearing against the web on one side of the line of severance. An adjusting screw 76 threaded in the holder 74 and bearing against the spreader 65 serves to regulate 65

late the pressure of the spreader on the paper web.

The spreaders 65 are desirably arranged approximately symmetrically to the center of the web, and are made to extend so that half of these spreaders act in one direction and the other half act in the opposite direction. This is especially desirable in cases where the machine is set to cut narrow strips, and therefore carries a comparatively large number of spreaders.

Also adapted to move with the slitting knives 14 away from the paper web are two trim guides 80 (Figs. 3 and 4) disposed adjacent the end trimming knives. These trim guides 80 serve to direct the side trimmings C of the web in a well regulated path outside the machine, so that these trimmings do not interfere with the orderly operation of the machine, and are in the form of arcuate plates secured to respective holder 81 fixed to clamps 82 adjustably mounted on the 20 spreader support bar 66.

As the slitter support bar 23 is moved axially to the left as shown in Fig. 1 upon rotation of the handle 41 from the full line position shown in Fig. 2, the arm 67 is moved with said support bar. However, since this arm 67 has a slide connection with the spreader support bar 66, this bar remains stationary so that the spreaders 65 and the trim guides 80 are not moved along the 30 surface of the paper, and therefore will not hook or tear the paper web.

While the machine is set in the normal operative position shown in Fig. 3, the knives 14 as well as the spreaders 65 and the trim guides 80 are locked against movement away from the paper on one side of the machine by the locking engagement of the lock pin 42 with the lock bracket 44, and on the other side by automatic locking of the arm 67. For locking this arm 67, the frame 11 has affixed thereto a locking pin 85 40 having an end portion extending inwardly from the inner face thereof, and the arm 67 has a socket 87 for receiving the projecting end of the locking pin 85 as the arm is moved toward the frame 11 by the endwise movement of the bar 23 into the operative setting of the machine as shown in Fig. 1. If desired, the socket 87 may be formed in a stud 86 set into an opening in the arm 67. The arm 67 is thereby locked against angular movement so that the support bar 23 is also locked against rotative movement without interfering with the axial movement of said support bar. Upon rotation of the crank handle 41 from the full line position shown in Fig. 2, the arm 67 is moved to the left as shown in Fig. 1 by the axial movement of the support bar 23, so that this arm 67 will move away from the pin 85 and out of locking engagement therewith. In this position, the arm 67 will be unlocked and can be rotated about the axis of 50 the support bar 23 by the angular movement of the lever 35 into the dot and dash position shown in Fig. 2.

The locking arrangement described also serves to automatically lock the slitting knives 14, the spreaders 65 and the trim guides 80 upon restoration of the lever 23 and the crank handle 41 in the full line position shown in Fig. 2. This automatic locking and unlocking operation of the knives 14 serves to reduce to a minimum the number of manipulative operations necessary to prepare the machine for a subsequent run.

It is immaterial whether the locking pin 53 be on the side frame and the socket 87 in the 75

arm 67, as their relative positions may be reversed.

As many changes can be made in the above apparatus, and many apparently widely different embodiments of this invention can be made without departing from the scope of the claims, it is intended that all matter contained in the above description or shown in the accompanying drawings shall be interpreted as illustrative and not in a limiting sense.

What is claimed is:

1. A slitter and rewinder comprising a set of slitting knives, means on one side of the machine for moving said set towards or away from the plane of the paper, and means on the other side of the machine operable automatically by the actuation of said first-mentioned means for locking said set against said movement or unlocking it to permit said movement.

2. A slitter and rewinder having two opposed overlapping sets of slitting knives between which the paper to be slit travels, means on one side of the machine for moving one of said sets laterally away from contact with the other set and then edgewise of the knives away from the plane of said paper, and means on the other side of the machine automatically operable when said movable set has been restored into operative slitting position for locking said movable set against movement away from the plane of the paper, and automatically operable when said movable set has been moved laterally away from operative slitting position for unlocking said movable set to permit it to be moved away from the plane of said paper.

3. A slitter and rewinder machine comprising two opposed overlapping sets of slitting knives between which the paper travels, a lever handle on one side of said machine, means operable upon actuation of said lever handle in one direction from normal position for moving one of said sets laterally away from the other set, means operable upon actuation of said lever handle in another direction for moving said movable set away from the plane of said paper, and means on the other side of said machine automatically operable when said lever handle is moved in said first-mentioned direction for unlocking said movable set to permit it to be moved away from the plane of said paper, and automatically operable when said lever handle has been restored to said normal position for locking said movable set against movement away from said paper plane.

4. A slitter and rewinder comprising two opposed sets of slitting knives between which the paper to be slit travels, one of said sets being movable laterally away from the other set along the plane of said paper, and subsequently away from the plane of said paper, a pin member, and a socket member adapted to engage and interlock with said pin member, one of said members being fixed while the other member moves with said movable set, said members being automatically interlocked when said movable set is in operative slitting position to lock said movable set against movement away from the plane of said paper, and automatically released upon movement of said latter set laterally from operative slitting position to permit movement of said movable set away from the plane of said paper.

5. A slitter and rewinder comprising a set of rotary slitting knives between which the paper to be slit travels, a bar eccentrically supporting

one of said sets, said bar being movable axially and rotatively, a pin member spaced from the axis of and extending parallel to said bar, and a socket member for said pin member, one of said members being fixed while the other member is movable with said bar into locking engagement with the fixed member when said bar is moved axially into operative slitting position to prevent rotation of said bar until after said bar has been axially moved from said operative position.

6. A slitter and rewinder comprising a pair of side frames, two opposed sets of rotary slitting knives mounted on and between said frames on opposite sides of the paper to be slitted, lever means adjacent to one of said side frames for moving one of said sets away from the plane of the paper, and means locking said movable set to the other frame against movement away from the plane of the paper in operative position of said movable set, said locking means being rendered automatically inoperative upon actuation of said lever means and being rendered automatically operative upon restoration of said lever means.

7. A slitter and rewinder comprising a pair of side frames, two opposed sets of rotary slitting knives mounted on and between said frames on opposite sides of the paper to be slitted, a bar eccentrically supporting one of said sets and journaled in said side frames for axial and rotative movement therein, a pair of levers secured near the opposite ends of said bar adjacent to respective side frames, means for locking said levers to their respective side frames in operative slitting position of said last-mentioned knife set, said locking means being automatically released upon axial movement of said bar from inoperative position, and automatically reestablished upon return of said bar axially into operative position.

8. A slitter and rewinder comprising two opposed sets of slitting knives between which the paper to be slitted travels, a bar eccentrically supporting one of said sets, said bar being axially and rotatively movable, a lever connected to said bar near one end thereof, a shifter shaft journaled in said lever and having an eccentric connection with said bar to cause axial movement of said bar upon rotation of said shaft, and means near the other end of said bar automatically locking said bar against rotation when said bar is moved axially into operative position, and automatically unlocking said bar upon axial movement of said bar away from operative position.

9. A slitter and rewinder comprising two opposed sets of slitting knives between which the paper to be slitted travels, a lever on one side of said set for moving one of said sets away from the plane of the paper upon angular movement of said lever, means for locking said lever against said angular movement, means carried by said lever for shifting said last-mentioned set laterally along the plane of the paper from operative position, means for releasing said locking means upon actuation of said shifting means, and means on the other side of said last-mentioned set automatically operable by the actuation of said shifting means for locking said latter set against movement away from the plane of said paper or for unlocking it to permit said latter movement.

10. A slitter and rewinder including a set of knives, a bar for supporting said knives, means

5 at one end of said bar for moving said bar endwise and thereafter oscillating said bar to impart corresponding movements to said knives, and means carried by said bar at the other end of the latter for locking said bar against oscillation and movable into and out of operative position by the endwise movement of said bar.

11. A slitter and rewinder machine comprising two opposed sets of slitting knives between which 10 the paper to be slitted travels, one or more trim guides, means connecting said trim guides and one of said knife sets for movement away from the plane of the paper, said latter knife set being movable laterally along the plane of the paper without causing movement of said trim guides, means on one side of the machine for moving said last-mentioned knife set laterally along the plane of the paper and then away from said plane, and means on the other side of the machine automatically operable upon lateral movement of said latter set into operative slitting position for locking said last-mentioned knife set against movement away from the plane of the paper, and automatically operable upon movement of said last-mentioned set laterally 15 out of operative position for releasing said knife set to permit its movement away from said plane.

12. A slitter and rewinder machine comprising two opposed sets of slitting knives between 20 which the paper to be slitted travels, one or more spreaders to separate the slit paper along its respective lines of severance, means connecting said spreaders and one of said knife sets for movement away from the plane of the paper, said latter knife set being movable laterally along the plane of the paper without causing movement of said spreaders, means on one side of the machine for moving said last-mentioned knife set laterally along the plane of the paper and then away from said plane, and means on the other side of the machine automatically operable upon lateral movement of said latter set into operative slitting position for locking said last-mentioned knife set against movement away from the plane of the paper, and automatically operable upon movement of said last-mentioned set laterally 25 out of operative position for releasing said knife set to permit its movement away from said plane.

13. A slitter and rewinder including a set of 30 rotary knives, a bar mounted for endwise and oscillatory movements, means for adjustably supporting said knives from said bar at spaced points along the length thereof, a pair of substantially parallel lever arms extending from said bar at opposite ends, means for moving said bar endwise with one lever arm and in respect to the other, separate locking means associated with said levers for normally preventing oscillation of said bar, and manually operable means for moving said bar endwise and simultaneously releasing both of said locking means.

14. A slitter and rewinder including a set of 35 power driven slitters, a set of friction driven slitters cooperating therewith, a pivotally mounted support for said second mentioned slitters, separate means at opposite ends of the machine for locking said support against swinging movement, and a single lever for releasing and engaging both of said locking means.

15. A slitter and rewinder including a set of 40 power driven slitters, a set of friction driven slitters cooperating therewith, a pivotally mounted support for said second mentioned slitters, separate means at opposite ends of the machine for locking said support against swinging move-

ment, and a single lever for releasing and engaging both of said locking means and for swinging said support.

16. A slitter and rewinder including a pair of power driven slitters, a second set of slitters normally in overlapping relationship to said first mentioned slitters, separate springs for each of the slitters of said second set for pressing them into frictional engagement with the slitters of the first set, a support for said second mentioned slitters and movable toward and from said first mentioned set, separate means at opposite ends of the machine for locking said support against movement, and a single member for releasing and engaging both of said locking means.

17. A slitter and rewinder including a pair of power driven slitters, a second set of slitters normally in overlapping relationship to said first mentioned slitters, separate springs for each of the slitters of said second set for pressing them into frictional engagement with the slitters of the first set, a pivoted support for said second mentioned slitters, separate means at opposite ends of the machine for locking said support against swinging movement, and a single member for releasing and engaging both of said locking means and for bodily swinging said support.

18. A slitter and rewinder comprising two opposed sets of slitting knives between which the paper to be slitted travels, means for moving one of said sets toward and away from the plane of said paper, means for normally locking both sides of said last mentioned set against movement away from said plane, and an operating member for actuating both of said means.

19. A slitter and rewinder comprising two opposed sets of slitting knives between which the paper to be slitted travels, means for moving one

of said sets toward and away from the plane of said paper, means for normally locking both sides of said last mentioned set against movement away from said plane, means for moving said last mentioned set in a direction parallel to the plane of the paper, and means for preventing said last mentioned movement when said last mentioned set is in operative position in respect to the other set.

10 20. A slitter and rewinder having two opposed sets of slitting knives between which the paper to be slitted travels, a trim guide, means connecting said trim guide and one of said knife sets for movement away from the plane of the paper and permitting lateral movement of said latter knife set along the plane of the paper without causing lateral movement of said trim guide, and a single lever mechanism for effecting both movements.

15 21. A slitter and rewinder having two opposed sets of slitting knives between which the paper to be slitted travels, a spreader, means connecting said spreader and one of said knife sets for movement away from the plane of the paper and permitting lateral movement of said latter knife set along the plane of the paper without causing lateral movement of said spreader, and a single lever mechanism for effecting both movements.

22. A slitter and rewinder having two opposed sets of slitting knives between which the paper to be slitted travels, an oscillatory support, means for securing one of said sets of knives in fixed radial relationship on said support, means for normally locking said support against oscillation, and a single lever for operating said locking means and for oscillating said support.
